CHALK TROUGH FOR CHALKBOARDS OR SIMILAR ARTICLES

John A. Cook, Montreal, Quebec, Canada, assignor to
Vilas Industries Limited, Cowansville, Quebec, Canada

Filed Jan. 23, 1967, Ser. No. 5,524

Claims priority, application Canada July 22, 1966

Term of patent 14 years

(Cl. D25—1)

FIG. 3

FIG. 2

FIG. 4

FIG. 1

FIGURE 1 is an end view of a chalk trough for chalkboards or similar articles according to my new design;

FIGURE 2 is a view in elevation of the chalk trough shown in FIGURE 1;

FIGURE 3 is a top plan view of the chalk trough shown in FIGURE 1; and

FIGURE 4 is a bottom plan view thereof.

I claim:

The ornamental design for a chalk trough for chalkboards or similar articles, as shown.
